US0D1010722S

(12) **United States Design Patent** (10) **Patent No.:** **US D1,010,722 S**
(45) **Date of Patent:** **** Jan. 9, 2024**

(54) **EYEGLASSES**

(71) Applicant: **Oakley, Inc.**, Foothill Ranch, CA (US)

(72) Inventors: **Lek Haagen Thixton**, Eastsound, WA (US); **Nicolas Adolfo Garfias**, Long Beach, CA (US)

(73) Assignee: **Oakley, Inc.**, Foothill Ranch, CA (US)

(**) Term: **15 Years**

(21) Appl. No.: **29/892,524**

(22) Filed: **May 18, 2023**

(51) **LOC (14) Cl.** **06-09**

(52) **U.S. Cl.**

USPC **D6/335**

(57) **CLAIM**

The ornamental design for eyeglasses, as shown and described.

DESCRIPTION

FIG. 1 is a top front perspective view of eyeglasses showing the claimed design;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan view thereof; and,

FIG. 6 is a bottom plan view thereof.

The broken lines in the figures show portions of the eyeglasses that form no part of the claimed design.

1 Claim, 5 Drawing Sheets
